MANTEL CLOCK CASE

John W. Smith, Millersburg, Ohio, assignor to
The Time Products Co., Berlin, Ohio

Application October 31, 1951, Serial No. 17,178

Term of patent 14 years

(Cl. D42—7)

To all whom it may concern:

Be it known that I, John W. Smith, a citizen of the United States, residing at Millersburg, in the county of Holmes and State of Ohio, have invented a new, original, and ornamental Design for a Mantel Clock Case, of which the following is a specification, reference being had to the accompanying drawing, forming part thereof.

Figure 1 is a front elevational view of a mantel clock case, showing my new design;

Figure 2 is a top plan view thereof; and

Figure 3 is an end elevational view of the same.

I claim:

The ornamental design for a mantel clock case, as shown.

JOHN W. SMITH.
